UNITED STATES PATENT OFFICE

2,436,191

ELECTRIC CIRCUIT BREAKER

Julius W. Timmerman, Jr., Springfield, Pa., assignor to General Electric Company, a corporation of New York

Application November 7, 1944, Serial No. 562,297

8 Claims. (Cl. 200—82)

1

My invention relates to electric circuit breakers, and more particularly to operating mechanisms for electric circuit breakers of the fluid operated type. Specifically my invention is an improvement on the circuit breaker operating mechanism disclosed and claimed in copending application Serial No. 562,296, Boisseau and Bold, filed concurrently with the present application and assigned to the same assignee as the present application.

A pneumatic or fluid operated mechanism for an electric circuit breaker should provide controlled opening forces that produce a high initial acceleration for rapidly separating the contacts and providing the necessary forces for opening blast valves and the like if the circuit breaker is an air or fluid blast circuit breaker. The opening speed should not be increased by virtue of the fluid blast at the contacts within the arc chutes acting upon the movable contacts as additional effective pistons. Neither should the speed be decreased by opposing forces encountered during the opening stroke. Near the end of the opening stroke it is furthermore desired that the speed be gradually decreased by a suitable dashpot arrangement.

Accordingly, it is an object of my invention to provide a new and improved fluid operated operating mechanism for electric circuit breakers.

It is another object of my invention to provide a fluid operated operating mechanism for electric circuit breakers which provides controlled pneumatic opening forces which produce a high initial acceleration for rapidly separating the breaker contacts to a desired opening speed which is gradually decreased after the arcing period until the contacts are arrested by a final dashpot action despite the assisting or opposing forces which might act thereon.

Still another object of my invention is to provide a new and improved fluid operated operating mechanism for air blast circuit breakers which is simple and compact and which provides all the speed control functions of accelerating, retarding, etc., throughout the operating strokes.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is an elevational view, partly in section, of an electric circuit breaker

2

embodying the operating mechanism of my invention; Fig. 2 is a side view of Fig. 1; Fig. 3 is an enlarged perspective view, partly in section, of the operating mechanism of Fig. 1, and Fig. 4 is an enlarged view, partly in section, of another portion of the operating mechanism of my invention.

As is discussed in the above referred to concurrently filed copending application, my invention is also particularly applicable to polyphase circuit breakers although it can equally well be used on a single phase circuit breaker.

Referring now to Figs. 1 and 2, I have illustrated my invention as applied to an electric circuit breaker which is particularly adapted for use with metal-clad switchgear. Accordingly I have illustrated a metal housing 1 within which is mounted a suitable arc chute 2, preferably supported on an insulator 3 suitably fastened to the base 4 of housing 1.

In accordance with the disclosure of Bold Patent 2,362,798, granted November 14, 1944, and assigned to the same assignee as the present application, the circuit breaker including the housing 1 constitutes a unit assembly with the interrupting structure, including the arc chute 2, at the lower end of the housing and the operating mechanism generally indicated at 5 supported at the upper end of the housing. As illustrated, the operating mechanism 5 and the source of fluid under pressure indicated on the drawing as tank 6 are supported from suitable channel irons 7 on the top of housing 1. As in the above mentioned Bold patent, a pair of horizontal ducts 8 and 9 are mounted intermediate the arc chute 2 and the operating mechanism 5. The exhaust gases from the arc chutes, such as 2, there being three such arc chutes for a three-phase breaker, are led through exhaust gas conduits such as 10, into ducts 8 and 9 which are suitably interconnected. These ducts 8 and 9 are connected to atmosphere, as is disclosed in the above mentioned Bold patent. Housing 1 is provided with a plurality of openings such as 11, arranged between ducts 8 and 9, through which the operating mechanism may be connected with the relatively moving contacts associated with arc chute 2.

Arc chute 2 preferably comprises the well known cross gas blast type of arc extinguishing structure, such for example as is disclosed in United States Letters Patent 2,284,842, Prince et al., granted June 21, 1942, and assigned to the same assignee as the present application. This arc chute may be constructed in accordance with

the arrangement disclosed and claimed in co-pending application, Serial No. 586,892, filed April 6, 1945, also assigned to the same assignee as the present application. Associated with the arc extinguishing structure, or arc chute 2, are a pair of relatively movable contacts comprising stationary contact 12 mounted within arc chute 2 and movable blade contact 13 adapted to engage the stationary contact 12 in arc chute 2 when the circuit breaker is in the closed position indicated in Fig. 1. Stationary contact 12 is connected by suitable conductors 14 and 15 with terminal 16 mounted exteriorly of housing 1, a suitable insulator 17 being provided to insulate the housing 1 from the live conductor. Similarly, movable contact 13 is connected by suitable sliding contact means with line terminal 18 through conductors 19 and 20, conductor 20 being suitably insulated in its passage through housing 1 by an insulator 21.

Straight line motion of movable contact 13 is obtained by virtue of a plurality of rollers 22, two rollers adapted to be engaged with either side of contact 13. Preferably rollers 22 are mounted in a suitable housing supported from an insulator 23, which in turn is mounted within housing 1 in any suitable manner.

Upon relative separation of contacts 12 and 13 an arc is drawn within arc chute 2 and this arc is extinguished by a blast of fluid such as air, or other gas, which moves in a direction substantially perpendicular to the axis of the arc. This blast of gas is supplied from tank 6 through conduit 24 which is provided with a section 25 constructed of insulating material so that the tank 6 and the operating mechanism 5 are maintained at ground potential and are completely insulated from the current conducting parts of the electric circuit breaker. A suitable blast valve generally indicated at 26, and best shown in Fig. 4, is mounted adjacent the point where conduit 24 enters tank 6. This blast valve 26 as is clearly indicated in Fig. 4, comprises a reciprocally movable valve member 27 fastened to a valve stem 28. A spring 29 normally biases valve member 27 to the closed position indicated in Fig. 4.

The new and improved operating mechanism 5 of my invention comprises parallel, double ended pistons and associated cylinders which drive and control the circuit breaker opening and closing strokes. As illustrated, the operating mechanism 5 which is essentially a plurality of fluid motors, comprises a main circuit breaker opening piston 30 and a circuit breaker closing piston 31 rigidly interconnected and suitably spaced from each other by a rack 32. Piston 30 is reciprocal in a cylinder 33 while piston 31 is reciprocal in a cylinder 34. Preferably these cylinders 33 and 34 are arranged as one continuous cylinder with a discontinuous portion so that a pinion 35 fixedly mounted on a horizontal, rotatable shaft 36 engages with rack 32. Reciprocal movement of pistons 30 and 31 causes rotation of pinion 35 and associated shaft 36.

In order to provide accurate speed control of the fluid motor, including main operating pistons 30 and 31, I have provided another set of pistons 37 and 38 rigidly interconnected by a rack 39. Pistons 37 and 38 are mounted in cylinders 40 and 41, respectively, which like cylinders 33 and 34, are preferably arranged as one continuous cylinder parallel with the continuous cylinder comprising cylinders 33 and 34. It will be obvious that with this arrangement when-

ever pistons 30 and 31 are moved to the right, as viewed in Figs. 1 and 3, pistons 37 and 38 will be moved to the left by virtue of pinion 35 whose teeth engage with both racks 32 and 39.

Pistons 37 and 38 provide a very desirable means of controlling the speed of operation of the operating mechanism 5 during an operating stroke of the circuit breaker, and eliminate the requirement of any separate dashpots or retarding devices as was required in prior art arrangements. Cylinder 40 is provided with a suitable needle valve 42, while cylinder 41 is provided with a suitable needle valve 43. These needle valves interconnect the respective cylinders with atmosphere and may be suitable adjusted to give the desired dashpot action, as will be described in greater detail hereinafter. Although I have illustrated pistons 30 and 31 which are the driving or main operating pistons, as of the same size as pistons 37 and 38, which in effect are compensating pistons, it will be obvious that pistons 30 and 31 may be larger than pistons 37 and 38 to ensure positive full opening and full closing operations.

The operating mechanism of any circuit breaker during the opening operation requires a relatively large initial force in order to separate the relatively movable contacts which are usually in frictional engagement. In addition an air blast circuit breaker such as is disclosed, usually requires additional forces to open the blast valve as will be described hereinafter. As soon as the contacts have separated and a blast of fluid is supplied in arc chute 2 for arc extinguishing purposes this fluid acts on movable contact 13 just as if movable contact 13 were a piston. If a constant force were applied against opening piston 30 sufficiently large to initially move contact 13 toward the open position, it is obvious that the air blast within arc chute 2 would soon assist piston 30 and cause contact 13 to move at a greatly increased speed. In order accurately to control the speed of movable contact 13 I provide an accelerating means comprising a booster or kick-off piston 44 conveniently mounted in a cylinder 45 coaxial with cylinder 33 and closely adjacent the end thereof. Piston 44 is provided with a piston rod 46 extending through the end of cylinder 33 so as to engage opening piston 30. Fluid under pressure from source 6 is provided in cylinder 45 through conduit 47 and circuit breaker opening valve 48. When circuit breaker opening valve 48 is open fluid under pressure enters cylinder 45 and causes booster piston 44 to move to the right. Any fluid in cylinder 45 ahead of piston 44 escapes to atmosphere through escape port 49. Although I have illustrated booster piston 44 as having the same diameter as main opening piston 30, it will be understood that piston 44 may have any size desired so as to provide the initial force which is desired.

In order to provide accurate speed control, predetermined points in cylinders 45 and 33 are interconnected by a suitable by-pass 50. Similarly, the fluid pressure entrance end of cylinder 45 is connected through a precharging conduit 51 with a predetermined point in compensating cylinder 40. Compensating cylinder 40 is also provided with a by-pass 52, the purpose of which 70 will become apparent as the following description proceeds.

In order to close the circuit breaker when in the open position fluid under pressure is supplied to circuit breaker closing piston 31 from source 6 through conduit 53 and circuit breaker closing

valve 54. For proper speed control cylinder 34, within which piston 31 reciprocates, is provided with an adjustable needle valve 55 and a pair of dump ports 56 the purpose of which will become apparent from the following description.

With the above described arrangement the movable contacts of a polyphase circuit breaker, such as 13, may readily be connected to operating mechanism 5 so as to provide a very simple and compact arrangement. As illustrated in Figs. 1 and 2, the horizontally mounted shaft 36 rotatable with pinion 35 is provided with suitable crank arms 57 rigidly fastened to shaft 36 at spaced points therealong, the spacing depending upon the spacing between the poles of the polyphase circuit breaker. The free ends of crank arms 57 are pivotally connected as is indicated at 58 with links 59. As indicated in Fig. 1, each link 59 comprises a section 59' of insulating material and a goose-neck portion 59" between crank arm 57 and insulation 59'. The other end of link 59 is pivotally connected, as is indicated at 60, with movable blade contact 13. It will be obvious that link 59 and crank arm 57 provide an over-center toggle arrangement which locks the circuit breaker both in the open and in the closed position. This locking feature is not my invention but is more fully disclosed and claimed in the above mentioned concurrently filed, copending application of Boisseau and Bold.

With the above described operating mechanism 5, blast valve 26 can readily be operated in response to relative movement of the contacts merely by providing a cam 61 fixedly attached to shaft 36, see Figs. 3 and 4. Cam 61 may be arranged to engage a roller 62 mounted on a bell crank 63 pivotally mounted at 64 to an extension 65 of metal clad housing 1. Bell crank 63 has an extension 66 engageable with blast valve stem 28. Upon rotation of shaft 36 in a clockwise direction as viewed in Figs. 3 and 4, cam 61 causes bell crank 63 to rotate in a counter-clockwise direction to open blast valve 26 and consequently to provide a blast of air or fluid under pressure adjacent relatively movable contacts 12 and 13 before these contacts have separated sufficiently to draw an arc therebetween.

It should be understood that cut-off switches and the like can also be controlled with the above described operating mechanism 5 merely by providing additional cams on shaft 36.

In order to understand how my new and improved operating mechanism provides the desired speed control, the opening operation of the circuit breaker will first be described. With the circuit breaker in the closed position indicated in Fig. 1, the opening operation is initiated by opening circuit breaker opening valve 48. It will be understood that this valve may be controlled in any suitable manner, such as electromagnetically or the like. A suitable control system for valves 48 and 54 is disclosed and claimed in copending application Serial No. 589,288, Timmerman and Bold, filed April 20, 1945, and assigned to the same assignee as the present application. Upon opening valve 48 fluid under pressure is admitted to the cylinder 45 to cause movement of booster piston 44. Coincidentally air is also admitted to the left-hand end of compensating cylinder 40 through precharging line 51. I have found it desirable to provide air from source 6 to booster cylinder 45 through a $\frac{1}{8}$ inch bore conduit, while the precharger line 51 is provided with a $\frac{3}{2}$ inch bore. It is obvious that with this arrangement and the fact that the volume to be filled in the

booster cylinder 45 is small, while the volume to be filled in compensating cylinder 40 is large, the pressure builds up rapidly behind the booster piston 44 which drives the piston 30 through piston rod 46 in the opening direction with an effective initial force.

No fluid under pressure is supplied to piston 30 during the initial stages of the opening stroke, for the only air permitted to enter cylinder 33 for the driving piston 30 must enter through, and be regulated by the restricting by-pass 50 for which I have found a suitable bore to be 0.36 inch. In other words, booster piston 44 provides a short preliminary power stroke at the end of which free expansion of its cylinder charge is effectively curtailed, but which charge nevertheless continues to be available for effective use upon piston 30 later in the stroke when it is most needed as will become apparent as the following description proceeds.

During the stroke of booster piston 44, the blast valve member 27 has been lifted by the cam 61 and the main contacts 12 and 13 have separated so that the air or fluid under pressure in the arc chute 2, acting on the bottom of contact blade 13, now constitutes an effective auxiliary motor for moving the contacts toward the open position. If a three phase breaker is considered, it will be appreciated that this opening force acting on the three contact blades 13 is considerable and tends to move the contacts with greatly increased and possibly undesirable speed as long as the blades 13 remain subject to the pressure within the arc chutes 2.

My invention in the particular embodiment being described is concerned with providing speed control in this range between the time when the fluid blasts in the arc chutes 2 may tend unduly to accelerate the opening movement of the circuit breaker and the moment at which these blades withdraw from the arc chutes. Accordingly, toward the end of the stroke of the booster piston 44 the compensating cylinder 40 becomes completely charged so that it begins to oppose the opening motion of the circuit breaker. The size of the precharger line 51 to the compensating cylinder 40 determines how soon and with what magnitude the opening compensating piston 37 opposes the now predominating opening forces applied to the contact blades 13 by the fluid under pressure within arc chutes 2.

The interrupting operation takes place within the arc chutes 2 while the compensating piston 37 is holding down the moving contacts to a substantially constant speed to which they have been accelerated by the short power stroke of booster piston 44. As the blades 13 withdraw from the arc chutes 2, the blast pressure is cut off by cam 61 so that the piston effect acting directly on the ends of the contact blades is discontinued, thus making the retardation of compensating piston 37 undesirable beyond this point; for it is preferable to continue the opening movement at the same predetermined constant speed. Accordingly, the restricted by-pass 52 is located so that it is uncovered by the compensating piston 37 as the blades 13 leave chutes 2 thereby relieving the opposing back pressure on piston 37 and venting the cylinder 40 to atmosphere. It is at this point in the stroke that the piston 30 becomes effective to take over full control to complete the opening stroke, for the restricted by-pass 50 from the booster cylinder has permitted but a gradual accumulation of air pressure behind the piston 30 during the time the contact blades 13 were sup-

plying an adequate opening force. This build-up of pressure commenced when piston 30, initially actuated under the urge of booster piston 44, began uncovering the by-pass 50 just as the booster piston 44 completed its short power stroke.

A final dashpot action takes place near the end of the opening stroke when the opening compensating piston 37 passes the second port of the by-pass 52. The air remaining in cylinder 40 is compressed, giving the required decelerating force. Needle valve 42 in the end of compensating cylinder 40 may be adjusted to allow the air to escape with the desired speed and at the same time insuring a positive full opening stroke. The needle valve 55 permits the air compressed in cylinder 34 during the circuit opening operation to escape.

A circuit breaker closing operation is initiated by opening circuit breaker closing valve 54 whereupon fluid under pressure is admitted into cylinder 34 to cause movement toward the left of piston 31. Dashpot action is exerted during the end of the closing stroke by means of the closing compensating or dashpot piston 38 in cylinder 41. Compression of the air contained in cylinder 41 at the beginning of the stroke affords this desired dashpot action. Needle valve 43 allows the air in cylinder 41 to escape with the desired speed near the end of the closing stroke in order to insure a positive full closing operation. The closing piston 31 drives the circuit breaker toward its closed position until the dump ports 56 are reached. At this point a large portion of the air is exhausted to atmosphere thereby permitting rapid reversal of the pistons in the event of a trip-free operation of the circuit breaker.

While I have shown and described a particular embodiment of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States, is:

1. In an electric circuit interrupter comprising a pair of relatively movable contacts, a first fluid operated motor including a cylinder and piston for producing relative movement of said contacts, an auxiliary fluid motor including a piston arranged initially to apply a mechanical force to said first fluid motor to cause relative separation of said contacts, means for introducing fluid under pressure only to said auxiliary fluid motor with reference to said above mentioned fluid motors to cause movement of both of said pistons and relative separation of said contacts, means including a cylinder for opposing the operation of said first fluid-operated motor during only the initial and final portions of the circuit interrupting operation, means for supplying fluid under pressure to said last mentioned cylinder prior to the introduction of fluid under pressure to said first fluid motor, and means responsive to movement of said piston of said auxiliary fluid motor for causing fluid under pressure to be introduced into said first fluid operated motor after a predetermined movement of both of said pistons.

2. In an electric circuit interrupter comprising a pair of relatively movable contacts, a first fluid motor including a cylinder and piston for producing relative movement of said contacts, an auxiliary fluid motor including a piston arranged initially to apply a mechanical force to said first

fluid motor to cause relative separation of said contacts, means for producing a blast of fluid adjacent said relatively movable contacts upon separation thereof to extinguish the arc drawn between said contacts, said blast of fluid tending to aid the separation of said contacts with one of said contacts effectively acting as a piston, means for introducing fluid under pressure only to said auxiliary fluid motor with reference to said above mentioned fluid motors to cause movement of both of said pistons and relative separation of said contacts, means for arresting said piston of said auxiliary fluid motor after a predetermined movement thereof, means responsive to movement of said piston of said auxiliary fluid motor for causing fluid under pressure to be introduced into said first fluid operated motor after a predetermined movement of both of said pistons, a third fluid motor for opposing the operation of said first fluid-operated motor during the initial and final portions but not during the intermediate portion of the circuit interrupting operation, and means for supplying fluid under pressure to said third fluid motor simultaneously with the introduction of fluid to said auxiliary fluid motor.

3. In an electric circuit interrupter comprising a pair of relatively movable contacts, a first fluid motor including a cylinder and piston for producing relative movement of said contacts, an auxiliary fluid motor including a piston arranged initially to apply a mechanical force to said first fluid motor to cause relative separation of said contacts, means for producing a blast of fluid adjacent said relatively movable contacts upon separation thereof to extinguish the arc drawn between said contacts, said blast of fluid tending to aid the separation of said contacts with one of said contacts effectively acting as a piston, means for introducing fluid under pressure only to said auxiliary fluid motor with reference to said above mentioned fluid motors to cause movement of both of said pistons and relative separation of said contacts, means for arresting said piston of said auxiliary fluid motor after a predetermined movement thereof, means responsive to movement of said piston of said auxiliary fluid motor for causing fluid under pressure to be introduced into said first fluid operated motor after a predetermined movement of both of said pistons, a compensating fluid motor for compensating for the effect of said blast of fluid on said one contact effectively acting as a piston, means for supplying fluid under pressure to said compensating fluid motor simultaneously with the introduction of fluid to said auxiliary fluid motor, and means for rendering said compensating fluid motor ineffective to retard said first fluid motor comprising a by-pass associated with said compensating fluid motor.

4. In an electric circuit interrupter comprising a pair of relatively movable contacts, operating means for said contacts comprising an accelerating means acting through a limited part of the movement of said contacts for quickly separating them, a fluid motor including a piston acting in a direction to continue the separation of said contacts, means for introducing fluid under pressure to said piston only after said accelerating means has initiated the movement of said contacts, and fluid means to oppose said contact movement during the initial portion and final portion but not during an intermediate portion of the circuit interrupting operation.

5. In an electric circuit interrupter comprising

ing a pair of relatively movable contacts, a fluid operated motor including a cylinder and piston for producing relative movement of said contacts, an auxiliary means arranged initially to apply a mechanical force to said contacts to cause relative separation thereof, means for rendering said auxiliary means ineffective after a predetermined movement thereof, means responsive to a predetermined movement of said auxiliary means for causing fluid under pressure to be introduced into said fluid operated motor after a predetermined movement of said contacts, and fluid operated means for opposing movement of said contacts during all but an intermediate portion of the opening operation of said circuit breaker.

6. In an electric circuit interrupter comprising a pair of relatively movable contacts, a first fluid operated motor including a cylinder and piston for producing relative movement of said contacts, an auxiliary fluid motor including a piston arranged initially to apply a mechanical force to said contacts to cause relative separation thereof, means for introducing fluid under pressure to said auxiliary fluid motor with reference to said above mentioned fluid motors to cause movement of both of said pistons and relative separation of said contacts, means for arresting said piston of said auxiliary fluid motor after a predetermined movement thereof, means responsive to movement of said piston of said auxiliary fluid motor for causing fluid under pressure to be introduced into said first fluid operated motor after a predetermined movement of said contacts, and fluid operated means for opposing movement of said pistons during all but an intermediate portion of the opening operation of said circuit breaker.

7. In an electric circuit interrupter comprising a pair of relatively movable contacts, operating means for said contacts comprising an accelerating means acting through a limited part of the movement of said contacts for quickly separating them, a fluid motor including a piston acting in a direction to continue the separation of said contacts, means for introducing fluid under pressure to said piston only after said accelerating means

has initiated the relative separation of said contacts, means for producing a blast of fluid adjacent said relatively movable contacts upon separation thereof to extinguish the arc drawn between said contacts, said blast of fluid tending to aid the separation of said contacts with one of said contacts effectively acting as a piston, and means for compensating for the effect of said blast of fluid on said one contact effectively acting as a piston only while said one contact is effectively acting as a piston.

8. In an electric circuit interrupter comprising a pair of relatively movable contacts, operating means for said contacts comprising an accelerating means acting through a limited part of the movement of said contacts for quickly separating them, a fluid motor including a piston acting in a direction to continue the separation of said contacts, means for introducing fluid under pressure to said piston only after said accelerating means has initiated the relative separation of said contacts, means for producing a blast of fluid adjacent said relatively movable contacts upon separation thereof to extinguish the arc drawn between said contacts, said blast of fluid tending to aid the separation of said contacts with one of said contacts effectively acting as a piston, means for compensating for the effect of said blast of fluid on said one contact effectively acting as a piston, and means for rendering said compensating means ineffective upon cessation of said blast of fluid.
